UNITED STATES PATENT OFFICE.

CHARLES G. TIEFEL AND LEONARD TIEFEL, OF ROCHESTER, NEW YORK,
ASSIGNORS OF ONE-THIRD TO EDGAR H. WARREN, OF SAME PLACE.

EXTENSION-LADDER.

SPECIFICATION forming part of Letters Patent No. 431,014, dated June 24, 1890.

Application filed March 1, 1890. Serial No. 342,183. (No model.)

To all whom it may concern:

Be it known that we, CHARLES G. TIEFEL and LEONARD TIEFEL, of the city of Rochester, county of Monroe, and State of New York, 5 have invented certain new and useful Improvements in Extension-Ladders; and we do hereby declare the following to be a full, clear, and exact description of the same, reference being had to the accompanying drawings, 10 forming a part of this specification, and to the letters of reference marked thereon.

Our present invention relates to that class of telescoping ladders capable of extension; and it consists in certain constructions and 15 combinations of parts whereby the operator is enabled to manipulate the ladder as desired from the ground and with the rope used for raising or extending it.

The invention further consists in certain 20 novelties of construction and combinations of parts whereby the construction of the ladder is materially cheapened and simplified, all as will be hereinafter fully described, and pointed out particularly in the claims at the end 25 of this specification.

In the drawings, Figure 1 is a perspective view of a ladder constructed in accordance with our invention; Fig. 2, a similar view extended; Fig. 3, a longitudinal section of a portion 30 of the ladder, showing the operation of the parts; Fig. 4, a view of a modified form of fastening device.

Similar letters of reference in the several figures denote similar parts.

The lower half or part A of the ladder is 35 provided with the side pieces A', connected by the rungs a at the front and at suitable intervals at the back by cross-pieces b, and between the sides is arranged the upper or 40 extensible portion B of the ladder, guided and held in the present instance between the rungs and connecting-pieces b, though it might be held and guided by suitable angle irons or straps arranged on the upper end of the 45 lower ladder and the lower end of the upper ladder, as is usual in devices of this description.

Arranged near the upper end of the lower ladder A, and preferably on the front of one 50 of the side pieces, is a pulley C, over which

extends a rope or cable H, connected at one end to the lower end of ladder B and extending to the bottom of the ladder again, by means of which the upper section can be controlled.

The preferred form of device for sustaining the ladder B when extended is shown in the first three figures of the drawings, and consists of a hook D, preferably made double and formed from a single rod or bar bent to form, two 60 hooks or supporting portions D' D', connected by a cross-bar d. The said hook is preferably pivoted to the side pieces A' by means of staples or similar connecting devices e, which embrace the substantially straight portions 65 d'. The hook portions D' D' are turned slightly upward, and when in normal position project through the ladder and in position to engage with any of the rungs of ladder B, being so positioned relatively to one of the 70 rungs a and the connecting-pieces b on the rear side that it will rest upon it and be firmly supported thereby, preferably causing the latter to support part of the weight of ladder B. One of the sides of the hook D is 75 provided with an arm E, having an aperture or eye F therein, projecting, preferably, though not necessarily, on the side of the pivotal point on which the hooks D' are located. The hoisting-rope H passes through this eye, 80 and thereby serves as a means for manipulating the hook from the ground.

In use the operator, when he desires to extend the ladder, simply pulls on the rope H, raising the ladder B, the rungs on the latter 85 engaging the hook and throwing it forward as they pass, when it will drop until the desired height is reached, when it will drop in place, and, engaging the back piece b, will securely maintain the ladder in place. When it is 90 desired to lower section B, the operator draws on the rope, taking the weight on it, and then pulls his end forward or in a direction to disengage the hooks, as in Fig. 3, and allows the rope to pass through his hands gradually. By 95 thus controlling the supporting-hooks by the hoisting-rope the operator can readily steady the section A with one hand and manipulate the upper section with the other.

To prevent the hook from getting out of 100

position accidentally, we prefer to pass the rope H between the connecting portion d and the rung a, though this is not essential, as the hook is under the control of the operator by the means described. However, in the modification shown in Fig. 4, where the engaging portion of the hook is above the pivotal point, this is a desirable feature, as in this construction the hook might fall backward when the ladder is turned down.

It is not essential that the arm E of the hook be arranged on the same side of the pivotal point of the latter as the engaging portion, as if placed on the opposite side it would only necessitate a movement of the rope H in the opposite direction to cause the detachment of the hook.

By locating the pulley C on the face of the side piece A' and employing the double hook described the device shown can be readily constructed from ladders already on the market, without essential modification. Further, the double-hook arrangement is cheap, and being arranged on opposite sides of the front is not in the way of the person ascending the ladder.

It will be understood that, instead of making the outside section the lower or stationary one, by a simple modification this could be reversed and the outer section raised and lowered.

These ladders can be made very cheaply, and have been found in practice to answer the purpose admirably.

We claim as our invention—

1. The combination, with the lower ladder-section, the upper section sliding thereon, and a rope connected to the ladder for raising and lowering it, of a hook or catch for sustaining the movable section controlled by the rope and adapted to be engaged and disengaged by

the lateral movements of the latter, substantially as described.

2. The combination, with the lower ladder-section, the upper section sliding thereon, and a rope connected to the latter for raising it, of a hook or catch for sustaining the upper section, having an eye thereon through which the rope passes loosely, whereby the catch can be controlled by the lateral manipulation of the rope, substantially as described. 50

3. The combination, with the lower ladder-section, the upper section sliding thereon, and a rope connected to the latter for raising it, of the double hook or catch for sustaining the upper section, pivoted at the sides of the lower section, and having the arm with which the rope co-operates, whereby the upper section may be raised and the catch controlled, substantially as described. 55

4. The combination, with the lower ladder-section having the rungs and the supporting pieces at the back and the upper ladder-section sliding between them, of the hook or catch for engaging the rungs of the upper section, adapted to project across and engage both the rung and supporting-piece on the lower section, substantially as described. 60

5. The combination, with the lower ladder-section, the upper ladder-section sliding thereon, and the rope connected to the latter for raising it, of the double sustaining-hook having the connecting-bar, between which latter and the rungs of the ladder the rope passes, thereby preventing the displacement of the hook, substantially as described. 70
